DEVICE FOR SECURING TOOL HEADS
ON HANDLES

Alfred E. Hindle, Wickenburg, Ariz.

Application October 1, 1943, Serial No. 504,615

2 Claims. (Cl. 306—35)

The object of my invention is to provide an improved device for securing a hammer or other tool head on a handle by means which will prevent its coming off or working loose and which will leave no obstruction for catching in the clothing or other article when the tool is in use.

It is a special object of my invention to provide a device which will prevent the tool head from working loose under constant use and which will prevent any side motion or end motion of the head relative to the handle.

It is also my object to provide a device which will hold the hammer or other tool head secure to the handle even where it is in use in temperatures of 130 to 135 degrees.

I attain the objects of my invention by the device illustrated in the accompanying drawing, in which—

Figure 1 is a side elevation of the invention with a portion of the hammer head broken away and shown in section;

Fig. 2 is a section taken longitudinally on line 2—2 of Fig. 1;

Fig. 3 is a section taken longitudinally through the tool head and transversely of the handle on line 3—3 of Figure 1;

Fig. 4 is a detail side elevation of the handle before the tool head is applied;

Fig. 5 is a transverse section through the handle on line 5—5 of Fig. 4; and

Fig. 6 is a perspective view of one of the metal plates that secure the tool head to the handle.

Like numerals designate like parts in each of the several views.

Referring to the accompanying drawing 1 designates a tool head such as a hammer head shown which is mounted on the handle 2. The tool head 1 has opposite recesses 3 in the end of the head. I provide opposite rectangular metal plates 4 each of which has a central slot 5. The plates 4 seat in correspondingly shaped recesses 6 in the opposite sides of the handle. The wooden handle has rectangular wooden keys which are left an integral part of the wood handle in the center of recess cut for the metal plates to seat in the slots 5 of metal plates 4, said ends 8 seating in the opposite recesses 3 of the end of the tool head.

In applying the tool, the metal slotted plates 4 are fitted over the wooden keys which are an integral part of the wood handle, into the recesses 6 which surround the wooden key. Then the tool head 1 is applied and then the projecting ends 8 of the metal plate are bent outwardly, as shown in Fig. 2 to align evenly with the outer end of the tool head.

As the wooden key ways 7 seat in the rec-

tangular slots 5 of the metal plates 4, side or end movement of the head is effectively prevented.

This tool head may be successfully used in temperatures of 130 to 135 degrees without the tool head coming loose, as expansion and contraction are taken care of at all times.

The fibres of the wood in the main section of the handle are not broken nor deformed, which lends strength and long life to the handle and prevents injury due to flying tool heads. In order to secure necessary strength and prevent shrinkage, the metal plates in width should be preferably 60 per cent of the length of the eye 15 in the tool head. Note that metal plates are installed to provide proper balance to the tool when in use, which is most important; and are installed on the sides of the eye of the tool head where width and strength are provided for metal plates, and by so doing overcome stress and strain on said metal plates. The residing force 20 on a tool head is at right angles to the length of the tool and perpendicular to the plane of the face of the tool head. In my invention the force 25 is still applied on solid wood. It does not throw any tension on any metal plates which might tend to flatten or deform them.

What I claim is:

1. The combination of a handle for hammers, 30 hatchets, sledges, axes, and like tools, having recesses on opposite sides containing two longitudinal wood keys which are left as integral parts of the wood handle when the aforesaid recesses are cut, like oppositely disposed metal plates fitting into the recesses, each plate containing a longitudinal slot to fit the wood keys of said handle, the metal plates having projecting ends bent into recesses in the tool head to lock the head in place on the handle and prevent its becoming loose, and whereby there are 35 no projecting ends to catch into objects.

2. The combination of a tool handle having recesses on opposite sides of the enlarged head of the handle, the handle having opposite longitudinal keys integral with the handle and surrounded by said recesses, metal plates shaped to seat in said recesses and having longitudinal slots to receive the aforesaid keys of the handle, the metal plates having projecting ends, recesses in the end of the handle into which the aforesaid projecting ends of the metal plates may be bent and seated to lock the head from becoming loose and to prevent any projecting 45 element beyond the end of the handle while securing the tool head to the handle.

ALFRED E. HINDLE.
